(57) **CLAIM**

The ornamental design for a candle lamp, as shown and described.

DESCRIPTION

FIG. 1 is a top perspective view of a candle lamp, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its state diagram;

FIG. 10 is its state diagram; and,

FIG. 11 is an enlarged detail view of area 11 in FIG. 1.

The broken lines in the drawings illustrate the portions of the candle lamp, which form no part of the claimed design. The dash-dot-dash broken lines encircling the enlarged views are for annotative purposes only and form no part of the claim thereof.

1 Claim, 11 Drawing Sheets
